UNITED STATES PATENT OFFICE.

WALTER JOSEPH FIDDES, OF TOTTENHAM, ENGLAND.

GAS WASHER OR SCRUBBER.

1,095,835.

Specification of Letters Patent.

Patented May 5, 1914.

Application filed December 26, 1913. Serial No. 808,872.

To all whom it may concern:

Be it known that I, WALTER JOSEPH FIDDES, a subject of the King of Great Britain, residing at Tottenham, England, have 5 invented certain new and useful Improvements in Gas Washers or Scrubbers, of which the following is a specification.

The object of this invention is to construct a gas washer or scrubber whereby a 10 more efficient washing or scrubbing of the gas is effected with a smaller quantity of liquid than is now the case.

My invention will be clearly understood 15 from the following description aided by the annexed drawings in which:—

Figure 1 is a sectional elevation of a complete apparatus. Fig. 2 is a section on line *a a* of Fig. 1. Fig. 3 is a section on line *b b* of Fig. 1. Fig. 4 is a section on line *c c* of 20 Fig. 1.

For the purpose of my invention I construct the apparatus in the form of a round tower or column having several superposed compartments 1, the floor 2 of each being 25 provided with a central opening 3 having a wall 4 around same. Down through the openings 3 in the floors 2, I pass a vertical shaft 5 which carries the agitators or beating appliances which are constructed as 30 hereafter described, and such shaft 5 is held in bearings 6 at top and bottom of the apparatus. These agitators or beating appliances are each constructed with a top plate 7 which fits around the shaft and is 35 secured thereto and with two or more other plates 8 preferably of the same diameter but having central holes 9 with flanges or walls 10 upstanding from their inner edges, the plates 8 being secured to the top plate 40 7 and below same by distancing pieces 11.

On the upper sides of the plates I secure angled rings 12 or walls concentrically curved or otherwise arranged and on the underside of the plates except the bottom 45 one, I also secure angled rings 13 or walls correspondingly arranged but with edges below the edges of the rings 12 on the upper sides of the plates. Between the rings 12 on the upper side of each top plate 7 and 50 on the underside of the floors 2 of the compartments I arrange angled strips 14 which dip below and between the edges of the aforesaid rings on the top plates. On each bottom plate I provide an annular lip 15 55 which surrounds the wall 4 of the hole 3 in the floor 2 and on each plate except the top

plate I provide two or more bent pipes 16, 17, which lead into the troughs formed between the upstanding flanges 10 and the first or innermost angled rings 12. 60

I employ one of these agitators or beaters in each compartment 1 and fix same to the vertical shaft 5 so that they can be revolved by the pulley 18. The top and bottom compartments do not contain an agitator and the opening 3 of the bottom compartment is made in the form of a stuffing box 19 which encircles the shaft 5 and forms a tight joint thereat to prevent escape of gas. 65

20 are valves in branch pipes 21 connecting each compartment with a pipe 22 for running off the liquid in the bottoms of the compartments when desired, such pipe 22 being in connection with the draw off pipe 23 of the bottom chamber which is connected with the outflow pipe by a seal pipe 24. 70

25 are radial vanes positioned in the bottoms of the compartments to prevent swirling of the water. 75

The gas to be washed or scrubbed is passed into the bottom of the tower at 26 and the water to clean or wash same is passed in at the top compartment of the tower by the seal pipe 27, the wall 4 on the 80 floor of each compartment retaining some of the water therein and forming a weir for the transfer of the water from one compartment to the other. The water in each compartment is also lifted into the troughs 85 of the agitators while the apparatus is at work so that the water before finally leaving the apparatus is acted upon by the gas many times whereby the water becomes 90 thoroughly impregnated. 95

The agitators or beaters are revolved at considerable speed and the water overflowing from the wall 4 of one compartment into the next below falls on to the top plate 7 within the central angled ring and at the same time the water in each compartment is being driven up the respective bent pipes 16, 17, into the central trough. The centrifugal action causes this water to spread outward, ride up the angled sides of the rings 12 and 100 strike the depending angled strips and rings 14, 13 on the underside of the floors and plates where it will be diverted into or against the angled wall of the next outer trough and so on against each angled wall 105 until it strikes the outer wall of the chamber 110 where it trickles down onto the floor to be

collected in the wells formed by the wall and the sides of the casing. This centrifugal action thoroughly breaks up the water into fine spray, and the gas in passing from the 5 bottom to the top of the apparatus passes up through the central holes 9 in the lower plates and then zigzag through between the plates and zig zag over the top plate to the next compartment and so on to the top of the 10 apparatus where it is passed away by the outlet 28 to the purifiers, the gas in passing through the spray becoming thoroughly washed or cleansed. Any number of compartments and agitators may be employed 15 in one apparatus according to the amount of gas to be treated.

By this invention I am constantly using the water in each compartment over and over again so that it becomes efficiently impregnated and the supply to each compartment due to the overflow at the weirs is determined by the amount of supply at the top of the apparatus.

I claim—

25 1. In a washing apparatus, the combination, with a casing containing a plurality of superposed, communicating compartments, and means for supplying thereto the substance to be washed and the washing medium; of an agitator arranged in each compartment and comprising a plurality of horizontal supports connected together in spaced, parallel relation and provided, each, with a series of concentric, angled rings; 30 and means for rotating said agitators.

2. In a washing apparatus, the combination and comprising a plurality of superposed, communicating compartments, and means for supplying thereto the substance to be washed and the washing medium; of an agitator arranged in each compartment and comprising a plurality of horizontal supports connected together in spaced, parallel relation, each of said supports, excepting the bottom support, being provided upon opposite sides, and the said bottom support being provided upon its upper side, with a series of concentric, angled rings; and means for rotating said agitators.

3. In a washing apparatus, the combination, with a casing containing a plurality of superposed, communicating compartments, and means for supplying thereto the substance to be washed and the washing medium; of an agitator arranged in each compartment and comprising a plurality of horizontal supports connected together in spaced, parallel relation, each of said supports, excepting the bottom support, being provided upon opposite sides, and the said bottom support being provided upon its upper side, with agitating elements; and means for rotating said agitators.

4. In a washing apparatus, the combination, with a casing containing a plurality

of superposed, communicating compartments, and means for supplying thereto the substance to be washed and the washing medium; of an agitator arranged in each compartment and comprising a plurality of 70 horizontal supports connected together in spaced, parallel relation, each of said supports being provided upon its upper side with a series of spaced, upstanding agitating elements, and each support, excepting 75 the bottom support, being provided upon its lower side with depending agitating elements which project into the spaces between the agitating elements on the next lower support; and means for rotating said agitators.

5. In a washing apparatus, the combination, with a casing containing a plurality of superposed, communicating compartments, and means for supplying thereto the substance to be washed and the washing medium; of an agitator arranged in each compartment and comprising a plurality of horizontal supports connected together in spaced, parallel relation, each of said supports being provided upon its upper side with a series of outwardly-inclined rings disposed in spaced, concentric relation, and each support, excepting the bottom support, being provided upon its lower side with depending agitating elements which project into the spaces between the rings on the next lower support; and means for rotating said agitators.

6. In a washing apparatus, the combination, with a casing containing a plurality of superposed, communicating compartments, and means for supplying thereto the substance to be washed and the washing medium; of an agitator arranged in each compartment and comprising a plurality of horizontal supports connected together in spaced, parallel relation, each of said supports being provided upon its upper side with a series of outwardly-inclined rings disposed in spaced, concentric relation, and each support, excepting the bottom support, being provided upon its lower side with a series of depending rings disposed and inclined similarly to the upstanding rings, each series of depending rings projecting into the spaces between the upstanding rings on the next lower support; and means for rotating said agitators.

7. In a washing apparatus, the combination, with a casing containing a plurality of superposed, communicating compartments, and means for supplying thereto the substance to be washed and the washing medium; of an agitator arranged in each compartment and comprising a plurality of horizontal supports connected together in spaced, parallel relation and provided, each, upon its upper side with a series of concentric, annular troughs, each support, except-

- ing the top support, being provided with a depending pipe which opens at its upper end into the innermost trough; and means for rotating said agitators.
- 5 8. In a washing apparatus, the combination, with a casing containing a plurality of superposed, communicating compartments, and means for supplying thereto the substance to be washed and the washing 10 liquid; of an agitator arranged in each compartment and comprising a plurality of superposed supports connected together and provided with upstanding agitating elements; depending agitating elements provided upon the top of each compartment for coaction with the adjacent upstanding agitating elements; and means for rotating 15 said agitators.
9. In a washing apparatus, the combination, with a casing containing a plurality of superposed, communicating compartments, and means for supplying thereto the substance to be washed and the washing liquid; of an agitator arranged in each compartment and comprising a plurality of superposed supports connected together and provided with coacting agitating elements;
- means provided upon the floor of each compartment to prevent swirling of the washing liquid therein; and means for rotating said 20 agitators.
10. In a washing apparatus, the combination, with a casing containing a plurality of superposed, communicating compartments, and means for supplying thereto the substance to be washed and the washing liquid; of an agitator arranged in each compartment and comprising a plurality of superposed supports connected together and provided with upstanding agitating elements; depending agitating elements provided upon the top of each compartment for coaction with the adjacent upstanding agitating elements; means provided upon the floor of each compartment to prevent 25 swirling of the washing liquid therein; and means for rotating said agitators.

In testimony whereof I have hereunto set my hand in presence of two subscribing witnesses.

WALTER JOSEPH FIDDES.
